B. L. MCNERNEY

ADJUSTABLE WRENCH

Filed July 10, 1923

Inventor

*Bernard Lynn McNerney
Beadbury & Caswell
Attorneys*

UNITED STATES PATENT OFFICE.

BERNARD LYNN McNERNEY, OF MINNEAPOLIS, MINNESOTA.

ADJUSTABLE WRENCH.

Application filed July 10, 1923. Serial No. 650,577.

To all whom it may concern:

Be it known that I, BERNARD LYNN McNERNEY, a citizen of the United States, residing in Minneapolis, in the county of Hennepin and State of Minnesota, have invented a new and useful Adjustable Wrench, of which the following is a specification.

My invention relates to improvements in adjustable wrenches.

- 10 Its object is to provide a simple, durable and efficient wrench including a pair of relatively movable end jaws and a pair of relatively movable handles or grips for manipulating the tool and adjusting said jaws.
- 15 A further object is to provide a tool of the present nature employing a reversible cam mechanism between the jaws and actuating handles, whereby said jaws may be quickly and easily opened and closed and firmly held by the handles in object gripping relation.

20 With the foregoing and other objects in view, which will appear in the following description, the invention resides in the novel combination and arrangement of parts and 25 in the details of construction hereinafter described and claimed.

25 In the drawings, Fig. 1 is a side elevation of a wrench embodying my invention; Fig. 2 is a plan view of the wrench; Fig. 3 is an 30 elevational view of the head of the wrench, the near cover plate being removed to expose parts otherwise concealed thereby; Figs. 4 and 5 are sectional views taken on the lines 4—4 and 5—5 of Fig. 2 respectively; Fig. 6 is a sectional view taken on line 6—6 of Fig. 4; Figs. 7 and 8 are detail views of the jaws, showing different relative positions thereof.

35 Referring to the drawings, it will be observed that my improved wrench includes a body A, end jaws b, c and handles 10, 11. The body consists of a block 12 and cover plates 13 reaching back from the sides of the block. Said block 12 is formed with 40 ways 14, 14^a therein arranged transversely of the body and in parallelism with each other and with said plates and is further formed with spaced, parallel guide slots 15, 15^a arranged longitudinally of said body.

45 A bolt 16 reaching through the block 12 and cover plates 13 and a bolt 17 reaching through the latter tie the said block and plates together, lugs 18 on the block fitting in notches 19 in the plates being provided to supplement said bolts in preventing relative movement between said block and plates.

The jaw b includes a head 20 and shank 21, a similar head 22 and shank 23 comprising the jaw c.

50 The shanks 21, 23 are slidable in the ways 14, 14^a in the block, the shank 21 having cam slots 21^a, 21^b therein, while the shank 23 is formed with cam slots 23^a, 23^b respectively reversed with respect and companion to said slots 21^a, 21^b in the shank 21. Said cam slots are arranged angularly with respect to the direction of movement of the jaws b, c. A pin 24 reaching through companion cam slots 21^a, 23^a in the shanks 21, 23 also extends through the guide slot 15 in the block 12. A similar pin 25 reaches through companion cam slots 21^b, 23^b in said shanks and extends through the guide slot 15^a in said block.

55 The handle 10, is rigidly secured to the rearward ends of the cover plates 13 by rivets 26 or other suitable means. The handle 11 is pivoted at its forward end between said cover plates by means of a pintle 27, said handle being enlarged at its pivoted end 60 to form opposed rocker arms 11^a and 11^b. A pair of links 28 join the ends of the pin 24, with the rocker arm 11^a and a second pair of links 29 join the ends of the pin 25 with the rocker arm 11^b, said links being pivoted on studs 28^a, 29^a on the rocker arms 11^a and 11^b. Recesses 12^a in the sides of the block 12 provide clearance spaces for the 65 ends of the pins 24, 25 and the forward ends of the links 28, 29. The swinging of the 70 pivoted handle 11, serves through the medium of the links 28, 29, and the co-action of pins 24, 25 with the cam surfaces of the slots 21^a, 21^b, 23^a and 23^b to open and close said 75 jaws b, c. The pins 24 and 25, guided by 80 slots 15, 15^a (Fig. 3) and co-acting with the cam surfaces of the slots 21^a, 21^b, 23^a and 23^b open and close the jaws (Figs. 7 and 8) 85 upon the swinging of the handle 11 and secure said jaws in variously adjusted positions, when said handle is held against pivoting movement.

90 A screw 30, threaded in extensions 10^a on the handle 10, provides an adjustable stop in the path of the rocker arm 11^b on the 95 pivoted handle 11. This stop variously limits the elevation of said handle 11 (Fig. 1) and the consequent separation of the 100 jaws b, c.

105 Ball bearings 31, seated in the heads 20, 22 of the jaws b, c bear against the front of the block 12, and rollers 32, journaled on 110

the block 12 at the rear thereof and forming bearings for the shanks 21, 23 serve to prevent the binding of the jaws *b*, *c* with the block 12.

5 In use, the swinging of the handle 11 adjusts the jaws to desired working positions. The gripping together of the handles 10, 11, in manipulating the tool, effectually holds said jaws against separation through the 10 medium of the links 28, 29, pins 24, 25 and cam surfaces of the slots 21^a, 21^b, 23^a, 23^b. The screw 30 may be employed to prevent the separation of the jaws *b*, *c* under strain and thereby relieve the user from gripping the 15 handles together for that purpose. Said screw may also be used to gauge the opening of the jaws and thus save loss of time in repeatedly applying the tool to a given object. Changes in the specific form of my invention, as herein described, may be made 20 within the scope of what is claimed without departing from the spirit of my invention.

Having described my invention, what I claim as new and desire to protect by Letters Patent is:

1. In a wrench of the class described, a body comprising a block and cover plates reaching back from the sides thereof, said block having ways therein arranged transversely of the body and in parallelism with each other and with said plates, said block being further formed with spaced, parallel guide slots arranged longitudinally of the body, a handle rigidly secured at its forward end to said plates between the same, a second handle, pivoted at its forward end between said plates, opposed rocker arms on the pivoted end of said second handle, a pair of end jaws, each including a shank 30 and a head thereon, said shanks being slideable in the ways in said block and having reversed companion cam slots therein, the same being arranged angularly with respect to the direction of movement of said jaws, 35 a pair of pins, one for each guide slot, said pins reaching through companion cam slots in said shanks and through their respective guide slots in said block, a pair of links for each pin, each pair of links serving to connect the ends of its respective pin with the end of one of said rocker arms, the swinging of the pivoted handle serving through the medium of said links and the co-action of said pins with the surfaces of said cam 40 slots to open and close said jaws, anti-friction bearings interposed between the jaws and block to prevent the binding of the former with the latter and an adjustable stop co-operating with the pivoted handle to variously limit the opening of the jaws.

2. In a wrench of the class described, a body having ways therein and spaced, parallel guide slots arranged at right angles with respect to said ways, a handle rigidly secured at its forward end to said body, a

second handle, pivoted at its forward end to the body, opposed rocker arms on the pivoted end of said second handle, a pair of jaws, each including a shank and a head thereon, said shanks being slideable in the 70 ways in said block and having relatively opposed cam slots therein, the same being arranged angularly with respect to the direction of movement of said jaws, a pair of pins, one for each guide slot, said pins reaching through companion cam slots in said shanks and through their respective guide slots in said block, a link for each pin, each link serving to connect its respective pin with the end of one of said rocker arms, 75 the swinging of the pivoted handle serving through the medium of said links and the co-action of said pins with the surfaces of said cam slots to open and close said jaws.

3. In a tool of the class described, a body 80 formed with a way therein, jaws on the body, one of said jaws being movable and having a shank slideable in said way, said shank being formed with a cam slot therein, handles for manipulating the tool, one 85 of said handles being pivoted on the body, a guide slot in the body extending longitudinally thereof, a pin movable in said guide slot and reaching through the cam slot in said shank, and an actuating link joining 90 said pin with said handle, the connection between said link and handle being offset from the pivotal axis of said handle.

4. In a wrench, a body, jaws on the body, one being slideable thereon and formed with 95 a cam surface, a member co-operating with said body and with said cam surface and adapted upon movement with respect to the body to shift the movable jaw, a handle hinged on the body, and means for moving 100 said member interposed between the same and said handle.

5. In a wrench, a body formed with a guide therein, jaws on the body, one being slideable thereon and formed with a cam slot 110 therein, a member co-acting with said slot and guide, a handle hinged on the body, and linkage joining said member and handle and operated by the latter to shift said slideable jaw upon hinging movements of the handle. 115

6. In a wrench, a body, jaws on the body, one being slideable thereon and formed with a pair of opposed angularly related cam surfaces, a handle hinged on the body, and a pair of jaw actuating devices co-acting 120 with said cam surfaces and operated in opposition to each other by said handle upon hinging movements thereof.

7. In a wrench, a body, jaws slideable on the body and having opposed angularly related cam surfaces thereon, a handle hinged on the body and jaw actuating means operated by said handle and co-acting with said cam surfaces to shift said jaws in opposite 125 directions.

8. In a wrench, a body, a pair of jaws slidable on the body, each jaw having a pair of cam surfaces thereon, the cam surfaces on each jaw being opposed, one to the other, and to the companion surfaces of the other jaw, a handle hinged on the body and a pair of jaw actuating devices operated in opposi-
tion to each other by said handle upon swinging movements thereof, each device co-acting with one set of companion cam surfaces on said jaws. 10

In testimony whereof, I have signed my name to this specification.

BERNARD LYNN McNERNEY.
